DYNAMOMETRIC JACK

Alvin H. Mann, Milbourne, Pa.

Application September 7, 1945, Serial No. 615,065

2 Claims. (Cl. 265—63)

(Granted under the act of March 3, 1883, as
amended April 30, 1928; 370 O. G. 757)

1

This invention relates to new and useful improvements in jack devices, and more particularly to jack devices of the dynamometric type especially adapted to apply loads to structures and structural members under test.

In numerous industries, and particularly the manufacture of aircraft, it is necessary that the various structures as well as their component members, be subjected to tests to determine, for example, the deflection, strength and other physical characteristics of the structure under a predetermined load, and thereby ascertain whether or not the structure conforms to the requirements of the specifications.

It has been the practice prior to the present invention either to load the structure with a dead-weight load, for example by placing bags of shot having the desired weight on the structure to be tested, or to place the test structure under the desired load by means of mechanical or hydraulic jacks of conventional design.

The use of bags of shot for this purpose is laborious and time consuming since each bag of shot must be carefully weighed and the several bags must be accurately distributed with respect to the test member or structure in order that the load thereof be properly applied and distributed with respect thereto. Furthermore, these bags of shot not infrequently break with the result that the shot becomes scattered over large areas causing additional delay and wastage of labor and time. On the other hand, the use of hydraulic and mechanical jacks of conventional design for this purpose is objectionable because of the inability to obtain true axial compression loading of the test member or structure that is entirely free of end moments with the result that accurate loading of the member or structure cannot be obtained.

With the foregoing in mind, the principal object of the present invention is to provide a novel dynamometric jack operable to effect true axial compression loading of structures that is entirely free from end moments.

Another object is to provide a dynamometric jack of the type described that requires a minimum amount of time and labor to install and operate.

A further object is to provide a dynamometric jack having the features and characteristics set forth that is of comparatively simplified construction, relatively inexpensive to manufacture, and highly efficient and accurate in operation and use.

These and other objects of the invention, and the various features and details of the construction, operation and use thereof, are hereinafter

2

fully set forth and described with reference to the accompanying drawing, in which:

Fig. 1 is a view in elevation of a dynamometric jack made according to the present invention; and,

Fig. 2 is a sectional view taken on line 2—2, Fig. 1.

A dynamometric jack made according to the present invention comprises a circular base 1, upon the upper face of which are complementary semicircular sections 2 and 3, respectively, having suitably formed semispherical recesses therein that cooperate to provide a spherical socket 4 in which is mounted the lower ball end portion 5 of a jack member 6. The ball portion 5 is relatively loosely mounted in the socket 4 so as to be substantially free to rotate therein within the limits defined by the wall portions 7 of the sections 2 and 3 surrounding the jack member 6.

10 The sections 2 and 3 are accurately centered with respect to each other coaxially of the base 1 by means of suitable tapered guide pins 8 and the sections are secured to the said base 1 by bolts 9.

Forming a part of the jack member 6 and extending from the ball portion 5 thereof outwardly of the socket 4 is a spindle portion 10 that terminates at its upper end in an enlarged portion 11 having horizontally therethrough suitable openings 12, arranged diametrically and at right angles to each other, to receive a bar (not shown) that can be actuated to rotate the jack member 6.

Upwardly of the portion 11 the jack member 6 terminates in a coaxial screw 13 of substantial length having a diameter smaller than the portion 11. Threaded on the screw 13 is a locking ring 14 provided with a knurled or otherwise roughened exterior circumferential surface as indicated at 15.

Also threaded upon the jack screw 13, endwise of the ring 14, is a piston member 16 having an enlarged head 17 slidably mounted in the chamber portion 18 of a cylinder 19. The cylinder 19 is provided with an upper chamber 20 of slightly reduced diameter that provides between said chambers 18 and 20 a shoulder 21 that functions as a stop to limit upward travel of the piston 16. Travel of the piston in a downward direction is limited by a ring 22 that functions also to retain the piston against displacement from the cylinder 19.

Positioned coaxially within the cylinder 19 so as to act between the cylinder-head wall 23 and the face of the piston head 17 is a coil spring 24 that operates to oppose movement of the piston inwardly of the cylinder when the jack member 6 is rotated to advance the piston 16 along its screw 13. The force exerted by the spring 24

when subjected to compression upon actuation of the piston 16 inwardly of the cylinder 19 is marked upon the exterior of the piston 16, as indicated at 25, for various positions of the piston 16 inwardly of the cylinder 19. The calibration markings 25 are interpreted with reference to the lower end face of the cylinder retaining ring 22 and the jacks of the present invention can be provided with springs of different strengths and corresponding markings 25 calibrated to meet the load requirements for any particular job.

The cylinder-head wall 23 projects radially beyond the adjacent cylinder wall to provide a flange 26 to which is secured an assembly 27 comprising a flange portion 28 and a coaxially extending tapered spindle portion 29 that terminates in a spherical ball portion 30. The ball portion 30 is rotatably mounted in a spherical socket 31 defined by a pair of complementary semicircular sections 32 and 33, respectively. These sections 32 and 33, and the socket defined thereby are constructed and arranged with respect to one another and the ball 30 therein, substantially as previously described herein with reference to the sections 2 and 3 defining the socket 4 in which the ball 5 is mounted. The sections 32 and 33 are centered with respect to the axis of a circular top plate 34 by means of tapered guide pins 35. Sections 32 and 33 and plate 34 are secured together by bolts 36.

Assembly 27 is made separable from the remainder of the jack in order that there can be interposed and connected between the flange 26 and flange 28 suitable spacer columns (not shown) of various lengths as required to provide a jack structure of sufficient length of span the distance between the floor or other fixed support and the member to be placed under load by operation of the jack in the described manner.

In operation of the dynamometric jack the device is disposed between a suitable fixed support and the member to be placed under load, for example, with the base 1 resting upon such fixed support and the top plate 34 in contact with the member to be loaded. A bar (not shown) then is inserted into one of the openings 12 of the jack member 6 and the latter is rotated by actuating said bar in the proper direction to rotate the jack member 6 and cause screw 13 to actuate the piston 16 inwardly of the cylinder 19 against the force of the spring 24. Initially, and until the piston 16 has been actuated to compress the spring 24 sufficiently, the piston 16 tends to rotate with the screw 13, in which event the piston 16 can be restrained against rotation by manually grasping the arm 37 projecting therefrom. However, as soon as the spring 24 is placed under load, the piston 16 ceases to tend to rotate with the screw 13 and the projecting arm 37 is released. The screw 13 is rotated to actuate the piston inwardly of the cylinder 19 against spring 24 until the latter exerts the desired load as indicated by reference to markings 25 and when the desired load is obtained the jack can be locked in that position by advancing the locking ring 14 along the screw 13 into engagement with the underside of the piston 16.

By reason of the novel construction and arrangement of parts of a dynamometric jack made according to the present invention and comprising the support assemblies provided endwise of the jack and between it and a fixed support and the member adapted to be placed under load,

such member or structure can be placed under a true axial compression load entirely free from end moments. The present invention provides a dynamometric jack that is operable to provide compression loading of structural members and structures in a true axial direction and entirely free from end moments. The invention also provides a device of the described type that requires a minimum amount of time and labor to install and operate. A dynamometric jack embodying the present invention is of comparatively simplified construction, relatively inexpensive to manufacture, and highly efficient and accurate in operation and use.

While a particular embodiment of the present invention has been illustrated and described herein it is not intended that the invention be limited to such disclosure and changes and modifications can be made therein and thereto within the scope of the claims.

The invention described herein may be manufactured and used by or for the Government of the United States of America for governmental purposes without the payment of any royalties thereon or therefor.

I claim:

1. A jack comprising a cylinder having a bore, a piston mounted for rotary and axial sliding in said bore, means limiting axial movement of said piston into and out of said cylinder independent of rotation of said piston, a spring in said bore between one end of said piston and one end of said cylinder, a handle on said piston external to said cylinder, a screw adapted to be threaded axially into and out of the other end of said piston, a ball on said one end of said cylinder, a ball on said screw, and sockets on said balls.

2. A jack comprising a cylinder having a bore open at one end and closed at the other end, 40 said bore adjacent the closed end being narrowed to provide a transverse shoulder, a piston having an enlarged head mounted for rotary and axial sliding in said bore with said transverse shoulder limiting axial movement of said piston 45 into said cylinder independently of rotation of said piston, detachable means in the open end of said cylinder of limiting movement of said piston out of said cylinder independently of rotation of said cylinder, a compression spring in said 50 bore between one end of said piston and the closed end of said cylinder, a detachable radially-extending handle on said piston external to said cylinder, markings on said piston corresponding with the force exerted by said spring at different positions of said piston, a screw adapted 55 to be threaded axially into and out of the other end of said piston, a ball on the closed end of said cylinder, a ball on said screw, and sockets on said balls.
